(57) **CLAIM**

The ornamental design for a rotatable case for electronic device with adjustable stand, as shown and described.

DESCRIPTION

FIG. 1 is a front perspective view of a rotatable case for electronic device with adjustable stand shown in the open position in a first configuration;

FIG. 2 is a front elevation view of the FIG. 1 device;

FIG. 3 is a rear elevation view of the FIG. 1 device;

FIG. 4 is a right-side elevation view of the FIG. 1 device;

FIG. 5 is a left-side elevation view of the FIG. 1 device;

FIG. 6 is a top plan view of the FIG. 1 device;

FIG. 7 is a bottom plan view of the FIG. 1 device;

FIG. 8 is a rear perspective view of the FIG. 1 device;

FIG. 9 is a front perspective view of the FIG. 1 device shown in the open position in a first alternate position, illustrating the device in use with a tablet computer;

FIG. 10 is a right-side elevation view of the FIG. 1 device in the first alternate position, illustrating the device in use with a tablet computer;

FIG. 11 is a front perspective view of the FIG. 1 device shown in a second alternate position, illustrating the device in use with a tablet computer;

FIG. 12 is a right-side elevation view of the FIG. 1 device in the second alternate position, illustrating the device in use with a tablet computer;

FIG. 13 is a front perspective view of the FIG. 1 device shown in a third alternate position where the case is rotated 90 degrees counterclockwise from its position in the FIG. 1, illustrating the device in use with a tablet computer; and, FIG. 14 is a right-side elevation view of the FIG. 1 device shown in the third alternate position, illustrating the device in use with a tablet computer.

The broken lines are for illustration only and form no part of the claimed design.
